UNITED STATES PATENT OFFICE.

WILLIAM JOHN RICKETS, OF LONDON, ENGLAND.

CONTROLLING AND REGULATING SYSTEM FOR DYNAMOS.

Application filed April 14, 1920. Serial No. 373,764.

To all whom it may concern:

Be it known that I, WILLIAM J. RICKETS, a subject of the King of Great Britain, and resident of London, England, have invented 5
5 a new and Improved Controlling and Regulating System for Dynamos, of which the following is a full, clear, and exact description.

This invention relates generally to improvements in controlling and regulating systems for dynamo electric devices to effect a substantially constant voltage at and above certain critical speeds, and under varying loads. More particularly, this invention relates to a thermionic means of effecting the control and regulation of dynamo electric machines.

One of the objects of this invention is to provide a means of controlling and regulating dynamo electric devices by utilizing the properties of a thermionic means as for instance an electron tube or a uni-laterally conductive valve tube of the incandescent cathode type. Broadly stated, as a voltage regulator, a filament of the valve which serves as the source of electrons therefore, is suitably connected to be subject to the varying voltage of the dynamo electric machine, and a second or plate element of the valve 25 is suitably connected to a winding or other means which serves to maintain a proper field strength for voltage regulations at certain critical speeds and at varying loads.

A further object of this invention is to provide a thermionic means in combination with a dynamo electric machine and a battery whereby the charging of the battery is controlled, the current to the battery being interrupted when same is fully charged, and the reverse flow to the generator being at the same time prevented. This is accomplished without the use of any mechanical moving parts, by utilizing the unilateral conductive property of the valve, 40 together with the control feature.

The invention consists in the arrangement and combination of devices, certain practical embodiments of which are shown in the accompanying drawings hereinafter more fully described, and particularly set forth in the appended claims.

In the accompanying drawings forming

a part of this specification, and showing for example certain practical embodiments of the invention, similar characters of reference designate corresponding parts in the several views.

Figure 1 is a diagram showing the application of a valve tube as a regulator for a dynamo electric machine, together with a battery.

Figure 2 is a modified form in which a plurality of independent windings are provided on an armature.

Figure 3 is a diagram of a modified form in which a differential relay is used.

Figure 4 is a diagram showing a modified form for effecting control of the current for the incandescent cathode.

With reference more particularly to Figure 1 of the accompanying drawings showing for example a practical embodiment of the invention, an armature 1 of a dynamo electric machine is shown together with positive and negative terminals 2, 3, respectively therefor. A thermionic means, or a uni-laterally conductive valve tube 4 of the incandescent cathode type is shown as comprising a filament cathode 5 having terminals 6 and 7 and an anodic sheath, plate or like electrode 8. As shown, the filament is connected in series with the shunt field winding 9 of the dynamo electric machine, one terminal of the field 10 being connected with the positive terminal 2 of the dynamo, the other terminal 7 of the filament 5 being connected with the negative side 3 of the dynamo.

Preferably, an adjustable resistance 11 is connected in shunt with the filament, so as to better effect control of the current therethrough. Across the main line terminals 12 and 13 is connected a storage battery 14, the positive terminal 15 is connected to the line wire 12, the other negative terminal 16 of the battery being connected with the other line wire 13, and the common blade 17 of a throw over switch including the two contacts 18 and 19, the former of which is connected with another anodic plate element 20 of the thermionic means, the contact 19 being connected with the negative terminal 3 of the generator through a series winding 21. The purpose of the throw-over switch 17 is to enable the

current to flow through the filament 5 and the shunt field winding 9 when the switch 17 is closed, and to enable the current to flow through the filament 5 and the series winding 21 when the switch 17 is open. The switch 17 is controlled by a suitable switch 22 which is connected with the filament 5 and the series winding 21.

When the switch 17 is closed, the current flows through the filament 5 and the shunt field winding 9, and the current flows through the filament 5 and the series winding 21. The current through the filament 5 is controlled by the adjustable resistance 11, and the current through the shunt field winding 9 is controlled by the switch 22.

When the switch 17 is open, the current flows through the filament 5 and the series winding 21. The current through the filament 5 is controlled by the adjustable resistance 11, and the current through the series winding 21 is controlled by the switch 22.

battery 14 to be suitably connected through the thermionic means with the generator for charging, as for instance when the switch is in the position indicated in Figure 1 in contact with 18, or to permit the battery 14 to be connected to the generator 1 which may be connected to a prime mover as for instance a gas engine, through the series field 21, so that the said battery may drive the dynamo 1 as a motor. In operation, when the switch 17 is in the position indicated in Figure 1, the filament 5 is connected in series with the shunt field 9, so that at a predetermined speed, the filament will be come incandescent, causing electrons to be emitted, which will enable a current to pass through the anode 8 and a counter winding 22, which winding is arranged to magnetically oppose the shunt winding 9. Thus, up to a certain speed excitation of the field coil 9 increases in the usual manner in shunt dynamos, but when this current reaches a certain value the cathode filament 5 in series with the field coil 9 or other suitable resistance, becomes increasingly incandescent, which in turn increases the conductivity through the anode plate 8, enabling an increased current to flow through the counter winding 22 which prevents further increase in field excitation. It is to be understood that the relative strength of the shunt winding 9 and the counter winding 22 may be varied, so that they may be so proportioned that the counter winding 22 may entirely neutralize a tendency of the shunt field winding to increase the field excitation. Thus it may be possible to maintain a relatively constant voltage at or above a given predetermined speed. If the speed and voltage on open circuit be plotted as a graph, the voltage approaches a certain limit asymptotically.

As shown in Figure 1, the battery 14 will be charged through the plate 20, which functions to prevent any reverse flow of current if the dynamo is stopped, or the battery becomes charged, but becomes conductive in the charging directions when the machine obtains the correct speed, or when the battery becomes partially discharged. It is thus seen that an automatic cut-off for a battery current is provided without the use of any mechanically moving parts. By the use of a bi-anodal valve, voltage regulation and battery control are effected. By the provision of a throw-over switch to insert a series winding, it is possible to use the battery as a starter for a prime mover as for instance a gas engine, which may be connected to the dynamo.

A modified form of the circuits is shown in Figure 2, in which an armature is provided with a plurality of independent windings 23-24, each winding being connected with a separate pair of brushes 25, 26 and

27, 28 respectively, one of the windings 23 being connected with the line terminals 12 and 13 of the output circuit, the other winding 24 being connected to the shunt field winding 9' through the filament 5 of the valve tube 4, the positive brush 27 also being connected to one end of the counter winding 22, the other end of the counter winding being connected with the anodic plate 8. The other plate 20' is connected to the battery 14 through the contact 18 and circuit closer 17. The negative brushes 28 and 26 of the respective windings may be connected by the conductor 29. The series field 21 may be connected to the contact 19 of the throw-over switch so that the series field properly wound may be used if desired in the manner above noted in connection with Figure 1. By providing the two independent windings 23 and 24, the latter is preferably of a higher voltage than the winding 23 supplying the output circuit, so that it would enable less current to be used for the field control and excitation and hence a lower amperage valve can be used. By connecting the negative brushes of the doubly wound armature, such an arrangement permits the bi-anodal valve to be used for both battery current and field current control. If desired, it is possible to connect the two windings 23 and 24 in series, in which case the positive brush 27 would be connected directly with the main terminal 12, and the terminal of the shunt winding connected with the positive brush 25, the resistance and turns being suitably proportioned. The negative brush 28 may be connected to the positive brush 25, as indicated by the dotted conductor 30, and the cathode 5 would be connected to the negative brush 26.

Another modified method of connecting the anode is shown in Figure 3, in which the shunt winding 9' is connected in series with a ballast resistance 31 which preferably is formed of a material having a positive temperature co-efficient, which accentuates the action. The cathode 5 may be suitably connected through an adjusting resistance 11 which may advantageously be composed of material having a negative temperature coefficient. The anodic plate 8 is connected to a junction point 32 between the ballast resistance 31 and the shunt winding 22. The action of such an arrangement being that when the filament 5 reaches incandescence, and the valve becomes conductive, an increased current passes from the plate 8 through the ballast resistance 31 to the generator, which consequently causes a voltage drop across the field winding 9', thus preventing an increase of field strength with increase of speed, and maintaining a relatively constant voltage. The connections of the battery switch and series winding may be arranged as previously set forth, so no ref.

erence is here specifically made thereto. If desired, the ballast resistance 31 may comprise one winding of a differential relay having another winding 33 connected in series 5 with the battery, whereby a circuit closer 34 is controlled which serves to automatically connect the battery in a well known manner with the dynamo when the voltage is sufficient, and will disconnect the same on 10 a slight reversal of current. Such an arrangement eliminates the necessity of having to carry the battery charging current through the valve, thus eliminating a voltage drop across the valve.

15 A modified form of valve arrangement is shown in Figure 4, in which a plurality of valves 34 and 34' are shown, a suitable adjusting resistance 35 being connected in series with one of the filaments 36, the said series circuit being arranged in parallel with the filament 5 of the other valve 34, such a circuit in turn being connected in shunt with the adjustable resistance 11. Such an arrangement having a plurality of valves 20 34-34' each having an anodic plate electrode 8 and 37 respectively, may be arranged in place of the bi-anodal valve used 25 in the circuit heretofore referred to.

If desired, the valves having the filament 30 therein may advantageously be used to serve as signal lamps, by mounting in a suitable guard casing in front of the pilot or driver in automobiles, boats, airplanes, and the like.

35 It is thus seen that by the use of the valves as herein set forth, for purposes of regulation, that relatively constant voltage is effected at or above certain speeds. This is effected primarily by utilizing the variable 40 conductive properties of the valve.

It is to be understood that any of the well known valves of the incandescent cathode type may be provided, and that they may either be exhausted or filled with gases such 45 as argon, neon or helium. It is to be further understood that the thermionic means for effecting voltage regulation is not limited to the charging of batteries, this merely being shown as one illustrative example of the application, it being understood that it may 50 have various other applications.

While certain practical embodiments of the invention have herein been shown, it is to be understood that various changes and 55 modifications may be made without departing from the spirit and scope of this invention.

Having thus described my invention, what I claim as new and desire to secure by 60 Letters Patent, is;

1. The combination of a current generating means having a shunt field, a thermionic means having a cathode and an anode, a ballast resistance connected in series with the 65 shunt field, and a second resistance, the sec-

ond resistance being connected in series with the cathode, the anode being connected to a point between the ballast resistance and the shunt field whereby at a predetermined voltage there will be an increase of current 70 through the anode and the ballast resistance, thus causing a change in the voltage across the shunt field to maintain a relatively constant voltage at the terminals of the generating means independent of an increase in 75 speed.

2. The combination of a generator having a shunt field, a resistance in series with the field, and a thermionic means having an incandescent cathode connected across the 80 generator, and an anode plate connected at a point between the shunt field and resistance in series therewith, whereby with increased generated voltage, a decreased drop across the shunt field is effected, thus maintaining a 85 substantially constant voltage at and above a certain speed.

3. The combination of a dynamo, a shunt field winding, and a resistance in series with each other shunted across the terminals of 90 the dynamo, and a thermionic electron discharge device having a filament shunted across the terminals of the dynamo, said device having an anode connected to the circuit containing the shunt winding. 95

4. In combination, a dynamo electric machine, a thermionic discharge device having a filament and an anode, a shunt field winding, and a resistance in series with each other, the filament of the thermionic device 100 being shunted across the terminals of the dynamo, and the shunt winding and series resistances being also shunted across the terminals of the dynamo, the anode of the thermionic device being connected to a point between the shunt winding and its series resistance. 105

5. In combination, a dynamo electric machine, a thermionic discharge device having a pair of electrodes, a shunt winding and a 110 resistance in series with each other, one electrode of the thermionic device being connected across the terminals of the dynamo, the shunt winding and the series resistance also being connected across the terminals of 115 the dynamo, the other electrode of the thermionic device being connected to a point in the circuit containing the shunt winding and the series resistance.

6. In combination, a dynamo electric machine, a thermionic device having a filament and an anode, the filament being connected across the terminals of the dynamo, a shunt winding and a resistance in series with each other and shunted across the terminals of 120 the dynamo, the anode of the thermionic device being connected to a point between the shunt winding and the series resistance, and an adjustable resistance in series with the filament. 125

7. In combination, a dynamo electric machine, a shunt winding and a series resistance connected across the terminals thereof, said series resistance having a positive coefficient of resistance, a thermionic device having a filament and an anode, the filament being connected across the terminals of the

dynamo in series with the second resistance, said second resistance having a negative coefficient of resistance, the anode of the thermionic device being connected to a point between the shunt winding and its series resistance. 10

WILLIAM JOHN RICKETS.
